UNITED STATES PATENT OFFICE.

MARION F. DOUGHERTY, OF LOS ANGELES, CALIFORNIA, ASSIGNOR OF FORTY ONE-HUNDREDTHS TO W. H. WHITESELL, OF LOS ANGELES, CALIFORNIA.

THREAD HOLDER AND WAXER.

No. 897,822.

Specification of Letters Patent.

Patented Sept. 1, 1908.

Application filed September 16, 1907. Serial No. 393,241.

To all whom it may concern:

Be it known that I, MARION F. DOUGHERTY, a citizen of the United States, resident at Los Angeles, in the county of Los Angeles and State of California, have invented a new and useful Thread Holder and Waxer, of which the following is a specification.

This invention relates to a portable device adapted to hold a spool of thread, whereby 10 the thread is prevented from unwinding except when it is reeled off as required, and to furnish means for waxing the thread as it is being reeled off from the spool.

The device is compact and a spool of 15 thread held therein is prevented from rolling around; the thread is prevented from becoming tangled, and the device is suitable for use in the sewing room or in the household, constituting a useful and valuable adjunct of the work basket.

The accompanying drawings illustrate the invention, and referring thereto:—Figure 1 is a perspective view of the device, a spool of 20 thread being shown in position therein, the thread having been partially unreeled from the spool. Fig. 2 is a section on line x^2-x^2 Fig. 1.

The device comprises a substantially cylindrical casing 1 having an unconfined edge 2 30 and provided near each end with an inwardly extending projection 3. The casing 1 is formed of rather stiff but springy material, such as metal or celluloid, and by grasping the free edge 2 the cylinder may be expanded 35 to permit the spool of thread 4 to be inserted. The projections 3 are provided to prevent the spool from slipping out endwise and when the spool is in position the casing 1 grips the spool, as shown in Fig. 2, with a sufficient 40 pressure to prevent the spool from rotation therein except when turned in unreeling the thread, and in the unreeling operation the casing acts as a journal for the spool and the projections 3 are spaced apart so that the 45 spool may partake of the necessary amount of longitudinal movement.

Projecting forwardly from the lower portion of the casing 1 is an extension 5 having inwardly directed side flanges 6, thus forming a socket for a cake of bees-wax 7. The front portions of the flanges 6 are depressed, as shown, to prevent outward movement of the cake of bees-wax and also to form troughs

for guiding the thread 8 into cutting corners 9. The outer edge of the extension 5 may also be formed with a cutting edge 10.

In operating the device the case may be grasped in the left hand and the thread 8 may be pulled out by the right hand the distance required for a needle full, and as the 60 thread is pulled out it is drawn across or through the bees-wax 7 so that the action of unreeling the thread also serves to wax the thread. The required length of thread having been drawn out, the thread may then be 65 deflected, as indicated by dotted lines in Fig. 1, against the knife edge 10 or into either knife corner 9 and severed.

It is obvious that the spool of thread may be very easily inserted or removed from the 70 device and that when in position therein it is frictionally held from rotation and prevented from unwinding and the thread cannot become tangled. Moreover, the short end of the thread which projects from the spool 75 will stick in its groove in the bees-wax and thus be held taut. The action of drawing the thread over the bees-wax causes the thread to cut its own groove in the wax. It will be noted that as the thread is with- 80 drawn that the groove in the bees-wax through which the thread slides will cause a traverse movement to be imparted to the spool as the thread unreels therefrom, thus causing the spool to travel longitudinally 85 first in one direction and then in the other.

What I claim is:—

1. In a device of the character described comprising a substantially cylindrical casing adapted to receive a spool of thread, an extension projecting from the casing, and bees-wax in said extension through which the thread is adapted to be drawn and waxed.

2. A device of the character described comprising a substantially cylindrical casing formed of springy material and having an unconfined edge, said casing having near each end a projection which projects inwardly beyond the inner face of the cylinder, the said casing being adapted to receive 100 spools of various lengths and the said inwardly extending projections permitting the spool to slide endwise along the smooth inner surface of the cylinder while the thread is being unwound but preventing the spool 105 from sliding endwise out of the casing, and

an extension projecting from said casing formed with a thread cutting edge.

3. A device of the character described comprising an expansible cylindrical casing 5 adapted to receive and hold a spool of thread and formed with an extension having inwardly directed flanges adapted to receive a cake of bees-wax, the said flanges being depressed at their forward portions to form

thread guiding troughs, and the said extension having one or more cutting edges. 10

In testimony whereof, I have hereunto set my hand at Los Angeles, California, this 10th day of September 1907.

MARION F. DOUGHERTY.
In presence of—

G. T. HACKLEY,

FRANK L. A. GRAHAM.
